Jesse C. Potts, Albany, N.Y.
Letters Patent No 165 dated 25th January 1848

The Schedule referred to in these Letters Patent
and making part of the same.

To all whom it may concern:

Be it known that I, Jesse C. Potts, of Albany in the County of Albany and State of New York, have invented or produced a new ornamental design for an airtight stove, and I do hereby declare that the accompanying drawing is a full and exact representation of a stove constructed after my said design, the sides and end not shown, being similar to those represented.

What I claim as my invention and desire to secure by letters Patent is the combination and arrangement of ornamental forms and figures represented in the accompanying drawing; forming an ornamental design for an airtight stove.
